PATIO BELL

Lorence O'Russo, 5311 Prospect, Peoria, Ill.

Filed June 25, 1964, Ser. No. 80,583

Term of patent 14 years

(Cl. D72—1)

FIG. 1 is a front elevation of a patio bell embodying my design;

FIG. 2 is a side elevation thereof looking at the bell of FIG. 1 from the right side thereof;

FIG. 3 is a top view thereof; and

FIG. 4 is an enlarged cross sectional view taken along the line 4—4 of FIG. 1, looking in the direction of the arrows.

The back of the face portion of the patio bell is plain. I claim:

The ornamental design for a patio bell, substantially as shown and described.
